UNITED STATES PATENT OFFICE.

OSCAR C. POPE, OF STOCKTON, CALIFORNIA.

FLORAL CARD HOLDER AND CLAMP.

1,188,012.

Specification of Letters Patent. Patented June 20, 1916.

Application filed April 26, 1915. Serial No. 24,027.

To all whom it may concern:

Be it known that I, OSCAR C. POPE, a citizen of the United States, residing at Stockton, in the county of San Joaquin, 5 State of California, have invented certain new and useful Improvements in Floral Card Holders and Clamps; and I do declare the following to be a clear, full, and exact description of the same, reference being had 10 to the accompanying drawings, and to the characters of reference marked thereon, which form a part of this application.

This invention relates to improvements in the means for attaching cards to floral pieces 15 and bouquets of all kinds, the object of the invention being to produce an efficient means for clamping the card to the flowers without the necessity of tying the same in various ways as is now the common practice which 20 requires a large amount of time and which has the disadvantage that very often the same become untied and lost.

A further object of the invention is to produce such a device as can be made attractive in appearance and at the same time 25 one which will efficiently fasten the card to the flowers.

A still further object of the invention is to produce a simple and inexpensive device 30 and yet one which will be exceedingly effective for the purposes for which it is designed.

These objects, I accomplish by means of such structure and relative arrangement of 35 the parts as will fully appear by a perusal of the following specification and claims.

On the drawings, similar characters of reference indicate corresponding parts in the several views.

40 Figure 1 is a top plan view of the complete device. Fig. 2 is a side elevation of the same. Fig. 3 is a view showing the practical application of the device.

Referring now more particularly to the 45 characters of reference on the drawings, I first provide a spring pressed clamp or clasp 1 having jaws 2 adapted to be held in frictional contact with each other by the pressure of the spring 3. The upper side of 50 the member 1 is provided with small bendable lugs 4, or other suitable means, for se-

curing to the clamp or clasp any ornamental design found desirable, such as a butterfly or other similar design 5.

Projecting outwardly from one face of the 55 clamp 1 is an extended flexible wire 6 made of any suitable material so it can be bent and unbent a number of times without breaking. In practice, the card or envelop containing the card, such as 7, is inserted over 60 the member 6 which is then bent, as at 8, in order to efficiently hold the card or envelop. The jaws 2 are then engaged with the floral piece in any suitable or appropriate place 65 where the frictional contact of the same will cause the device to be firmly clamped to the said floral piece until it is desired to remove the same.

From the foregoing description it can readily be seen that I have produced an 70 efficient structure for the purposes named and one which can be made in many attractive styles. It will further be seen that I have produced such a device as substantially fulfils the objects of the invention as set 75 forth herein.

While this specification sets forth in detail the present and preferred construction of the device, still in practice, such deviations from such detail may be resorted to as 80 do not form a departure from the spirit of the invention, as defined by the appended claims.

Having thus described my invention, what I claim as new and useful and desire to set 85 out by Letters Patent is:—

1. A device of the character described comprising a spring pressed clasp and a projecting member integral with one part of the clasp, such projecting member being 90 capable of being bent and twisted at will without breaking, as described.

2. A device of the character described comprising a spring pressed clasp, small bendable lugs on the edges of one part of 95 said clasp arranged to removably connect an ornamental design with the clasp whereby such ornamental design will hide the clasp when engaged with an object, as described.

In testimony whereof I affix my signature. 100

OSCAR C. POPE.
